UNITED STATES PATENT OFFICE.

HENRY J. BRINKMAN, OF MINNEAPOLIS, MINNESOTA, ASSIGNOR OF TWO-FIFTHS TO BENJAMIN O'NEILL, OF SAME PLACE.

MIDDLELINGS-PURIFIER.

SPECIFICATION forming part of Letters Patent No. 351,307, dated October 19, 1886.

Application filed January 16, 1886. Serial No. 188,707. (No model.)

To all whom it may concern:

Be it known that I, HENRY J. BRINKMAN, a citizen of the United States, and a resident of Minneapolis, in the county of Hennepin and State of Minnesota, have invented certain Improvements in Middlelings-Purifiers, of which the following is a specification.

My invention consists, generally, in the construction and combination hereinafter described, and particularly pointed out in the claims.

In the drawings forming part of this specification, Figure 1 is a vertical section of a machine that I have devised for carrying out my invention. Fig. 2 is a sectional end elevation of the same; Fig. 3, a detail of a modification. Fig. 4 is an enlarged detail.

In the drawings, 2 represents the casing of the machine, which is of suitable shape and construction. Within this casing is a vertical frame, 3, that is hung upon links 5, pivoted to the frame and to the inner walls of the casing or frame of the machine. Eccentric-shafts 7 are journaled upon the outside of the casing, 25 and connecting-rods 9 pass from the shafts into the casing and are connected to the frame 3. The shafts 7 are connected by belts 11, by which power is communicated from one shaft to the other. In order that the eccentrics 30 may move in unison, I provide a connecting-rod that is connected to a crank-pin upon a disk on the end of each crank-shaft. These eccentric-shafts are driven at a high rate of speed, and they give to the suspended frame 35 a rapid vibratory motion.

In the frame 3 are a series of inclined screens, formed of bolting-silk or other screening material. This silk is preferably secured by tacking it to wooden strips or bars 16, 40 fastened to the frame 3. A corrugated metal plate, 19, is arranged at a short distance from the silk, and on a plane substantially parallel with its surface. These plates are secured to the frame 3 in any suitable manner. I provide the inclined valves 25, which extend the full width of the screen and are pivoted to the sides of the frame 3. The material that goes over the screens falls upon these valves and slides down their inclined surface onto con-

ductors 27, arranged at the upper end of each screen below the first one. From the conductors 27 the material falls onto the upper part of the screen below, and so on through the machine. I prefer to arrange an inclined conducting-board, 29, beneath the upper part 55 of each screen. This board directs the material that passes through the screen onto the upper part of an inclined plate or board, 23, that extends from the lower end of one screen to the top of the next. Upon the board 23 60 are gather-boards 24, which direct the material into spouts 31, there being preferably a separate spout for each section of the screen. These spouts are provided with the valves 33, by means of which the material may be directed into any spout or spouts desired.

I provide means for jarring each section of the screen, in order to clear the same. A series of shafts, 35, are journaled across the frame in the rear of the screens, as shown in Figs. 70 1 and 4. Each of these shafts is provided with a knocker, 37, one at each side of the frame, in line with the strips to which the cloth is secured. Upon these strips I place the arched metal plates or bumpers 39, opposite the knockers on the shafts. The shafts revolve at a slow rate of speed, and when the knockers are in position nearest the frame 3 the bumpers are brought against the ends of the knockers, thereby giving a slight jar to the 80 section of the screen, which knocks off any adhering material. The knockers are preferably arranged at different points on the several shafts, so that only one set of knockers is in position for operating at the same time.

The shafts 35 are driven by a chain, 11, that passes over sprocket-wheels on the ends of the shafts. This chain preferably passes upon one side of one shaft and the opposite side of the next, as shown in Fig. 4.

A suction-fan, 21, is located in the casing, preferably near the lower end thereof, and the casing is made with closed walls on that side of the frame 3 in which the fan is located. The other side of the casing is open, so that 95 an air-current is produced through the screens under the corrugated plates and out at the ends thereof. The valves 25 may be adjusted

so as to regulate the current through the screens.

As the frame is rapidly vibrated back and forth the material is thrown from the surface 5 of the silk into and against the corrugations of the metal plate. This action detaches the bran and light particles from the grits, and the air-current keeps them above the grits and away from the silk. The grits thereby come 10 freely in contact with the silk. The air-current passes along beneath the corrugated plate, carrying the light material with it, and passes out under the ends of the plate. The air drawn out at the bottom of the plate carries 15 the light material over the edge of the valve 25. The current from the top of the plate passes over the conductor 27 and through the material that falls from the valve 25 onto this conductor. This current also takes with it 20 some of the light or fluffy material. A portion of the air is also drawn through the space above the valve 25. The result is that the light material—bran-scales, &c.—is fully detached from the middlings or grits, without 25 causing the latter to flour, and the material is thoroughly exposed to the air-currents, whereby the light stuff is carried away.

The plate or board 23 may have an opening through it, which is covered by a hinged valve, 30 24, as shown in Fig. 4. When this valve is raised, air passes through the sheet of material as it falls from the edge of the valve, and carries with it through the plate any small specks of light material that may pass through 35 the cloth. This portion of the current passes over the edge of the valve 25 and aids in aspirating the material that falls from the screen.

Instead of the corrugated plate, I may use 40 as beater bars or surfaces a series of strips that extend across the screens, at a short distance therefrom and in substantially the position occupied by the lower parts of the corrugations of the metal plates, as shown in Fig. 3. The material will be thrown back and forth between the silk and these bars, and the air-current 45 will pass directly through them, carrying the light material with it. The corrugated plates may be provided with a series of openings, and with regulating-valves, if desired. 50 In each instance as the material passes down the inclined screens it is thrown against beater-surfaces and at the same time subjected to a current of air that passes upward through the screen. The several screens or sections are of 55 progressively coarser mesh from the top toward the bottom.

A spiral conveyer, 81, is arranged beneath the screens to carry out the material that falls from the lower screen.

60 I prefer to provide an opening, 89, in the wall of the casing, which may be provided

with a suitable regulating-valve, through which air is admitted between the screens and the fan when it is desired to lessen the force of the current through the screens.

65

A suitable hopper is secured to the top of the main frame or casing. It is provided with a suitable gate, and the top of the frame 3 is provided with a feed-board, 85, over which the material is fed. An inclined board, 87, is 70 arranged beneath the feed-board, and aids in directing the material into the space between the silk and the corrugated plate.

It will be seen that the screens are arranged at a greater inclination than is usual in machines of this class. By this arrangement as the material passes down the screens smaller openings are presented to it than when the inclination is less, while the openings are presented in full size to the air-currents.

75

I claim as my invention—

1. In a middlings-purifier, the combination, with a vibrating frame, of one or more inclined screens carried by said frame, and beater-plates arranged over but not in contact with 85 said screens, as described, whereby the material is thrown against the beater-plates as it passes over said screens, for the purpose set forth.

2. The combination, with the vibrating frame and the series of inclined screens carried by said frame, of the corrugated plate arranged in said frame over said screens, and means for producing a current of air through 90 said screens, substantially as described.

95

3. The combination, in a middlings-purifier, with the vertical frame supported upon hang- 100 ers, and means for vibrating said frame, of the series of inclined screens carried by said frame, the corrugated plates secured to said frame over said screens, valves arranged below said plates, and means for producing a current of air through said screens, substantially as de- 105 scribed.

4. The combination, in a middlings-purifier, with a vertical frame supported upon hang- 110 ers, and means for vibrating said frame, of the series of inclined screens carried by said frame, a series of bumpers, 39, on said frame, a series of shafts, 35, and knockers 37, arranged at dif- 115 ferent angles on said shafts and adapted to engage said bumpers, for the purpose set forth.

5. The combination, in a middlings purifier, of a vibrating frame, a series of inclined screens carried by said frame, a series of beater-plates 115 mounted in said frame over said screens, and means for producing a current of air through said screens, substantially as described.

HENRY J. BRINKMAN.
